R. EDMONDSON.
MIXING MACHINE.
FILED APR. 17, 1922.

Robert Edmondson
INVENTOR

UNITED STATES PATENT OFFICE.

ROBERT EDMONDSON, OF ROCHESTER, NEW YORK.

MIXING MACHINE.

Application filed April 17, 1922. Serial No. 554,222.

To all whom it may concern:

Be it known that I, ROBERT EDMONDSON, a citizen of the United States, residing in Rochester, in the county of Monroe and State of New York, have invented certain new and useful Improvements in Mixing Machines, of which the following is a specification.

This invention relates to concrete mixing machines.

One object of the invention is to provide a concrete mixer that may be easily and freely rotated to mix concrete material, and tilt it to discharge the mixed material therefrom in such a way that the drum will not be disengaged from the parts by which it is rotated.

Another object of the invention is to mount the mixing drum upon a swinging support, so that the drum and support may be swung together when it is necessary to empty the drum.

A still further object of the invention is in making the mixing drum in two parts, the bottom part of thicker and heavier material, and the top part of thinner and stronger material. This will keep the greater part of the weight below the center, and keep the drum from being top-heavy.

With the above and other objects in view, the present invention consists in the combination of parts more fully described and illustrated in drawings, it being understood that changes may be made in the form, proportions, size and minor details, without sacrificing any of the advantages of the invention.

In the drawing Figure 1 is a vertical sectional view of the invention.

In Figure 2 is an end elevation, showing different portions of the drum in dotted lines.

The reference numbers (1) and (2) designate standards, each provided with a bearing (3) and (4) on its upper end, adapted to receive the corresponding trunnions (5) of the swinging cross bar (6).

The swinging U-shaped cross bar (6) is in one piece and is provided with a recess (7) in its upper face, with which communicates an opening (8) through the bottom of the cross bar, to receive the journal stud, (9) fixedly secured to the bottom of the drum (10) in any suitable manner.

The journal stud (9) extends into the recess (7) and through a bearing fitted in the

recess, comprising upper and lower parts, (11) and (12), and steel balls between at (13). The journal stud (9) extends through bearings and recess (7) and (8), in the cross bar and a thread is cut in lower end of stud (9), with a nut to hold journal stud in place at (14), whereby the drum has an easy and free rotation upon the swinging cross bar, regardless of whether the drum is in its normal position or swung downward, to provide for the rotation of the drum (10). I provide the same with an annular toothed rack (15) around the drum, which meshes with a pinion (16), carried at the inner end of a short shaft (17) extending through one of the ends of cross bar at (5), on top of standard (2), as shown in Figure 1.

At the other end of this shaft I provide a gear (18) to connect with any suitable driving means (not shown) to rotate the shaft and the drum through the rack and pinion connections (15) and (16) and (17) and (18) respectively. Thus the drum may be rotated on its axis (9).

The mixing drum (10) is concave and is in two parts, open at the top, joined together at (19) by bolts at (20). The lower part (21) is made of thicker and heavier material. The upper part (22) of lighter and stronger material. The object is to have the greater weight at the bottom, so that the drum will not be top-heavy.

Triangular shaped ridges extend vertically on the inside of the drum at (23) from a short distance from the bottom of the drum to a short distance from the top at (24) and (25).

The object in not placing ridges even with the top of drum is, when the drum revolves they would cast the mixing material out of the drum.

The mixing drum (10) when loaded and mixing revolves at an angle of fifty degrees (50°) as shown in Figure 2, in dotted lines. If the inside of the drum were smooth the material, if wet, would not turn over but would settle to the bottom of the drum.

In the present instance the ridges (23) take hold of the material from the under side, as the drum revolves, and carry it a certain distance up the side of drum and drop it at the top of mixing material, where it rolls back to the bottom of the drum.

After the material is mixed the swinging cross bar (6) is swung upon its trunnions

(5) through its bearings (4) at top of standard (2) by a gear at (26) and worm at (27).

Said worm gear (26) and (27) may be connected to any suitable power (not shown); by giving a number of turns of this worm gear to right or left the swinging cross bar will raise the bottom of the drum far enough to allow the mixing material to slide out of drum..

10 What I claim is:

1. A combination in a mixing machine comprising a body having a cylindrical upper portion and a reduced closed bottom portion with longitudinal ridges mounted upon the inner surface of said cylindrical portion and projecting into said bottom portion, a tilting substantially U-shaped cross bar in which said mixer is rotatably journaled, standards in which the end por-
- 15

tions of said cross bar are journaled, and 20 separate means for rotating said mixer and for tilting said cross bar.

2. A mixing machine comprising standards, a swinging bar having end journals with bearings in said standards, a mixer 25 drum mounted to rotate about its longitudinal axis, on said cross bar, one of said end journals being solid and the other being hollow, and separate means associated with said hollow journal for rotating said drum 30 and for tilting said cross bar.

In testimony whereof I affix my signature in the presence of two witnesses.

ROBERT EDMONDSON.

Witnesses:
